UNITED STATES PATENT OFFICE

PAUL LUNGSTRAS, OF ST. LOUIS, MISSOURI

MEASURING AND TAGGING DEVICE

Application filed March 16, 1929. Serial No. 347,487.

The object of my device is to make a measuring and tagging device to be used principally in laundries and dry cleaning plants. It finds particular application in the handling by such plants of articles that shrink in the washing and cleaning process. A more specific object is to enable a laundry or dry cleaning plant to return to the owner a shrinkable article, such as a lace curtain or drape, 10 in its original shape and with the original dimensions. With these and other objects in view my invention has relation to certain novel features of construction and arrangement of parts as will be hereinafter more 15 fully described, pointed out in the claim and illustrated in the drawings in which

Fig. 1 is a front elevation of my device and Fig. 2 is a plan view of my device and Fig. 3 is a front elevation of a tag used with 20 my device. Fig. 4 is a fragmental plan of a modified form of a portion of my device using pockets instead of hooks for the storage of tags. Fig. 5 is a fragmental front elevation of Fig. 4.

25 Numeral 4 designates a board conveniently secured to a wall breast high longitudinally. The securing means of the board to the wall form no part of my invention. Near one end of the board 4, preferably the left end, is secured the spring clamp 5 having the handle 6. To the right of the spring clamp 5 near the top of the board 4 and secured to the board 4 equi-distantly are positioned the hooks 7. The hooks 7 are of the conventional type being 30 preferably screwed or nailed to the board 4. From the center of each of the hooks 7 are drawn parallel vertical lines 8 terminating at the bottom of the board 4. The distance between the hooks 7 may be made any 35 convenient unit of length such as an inch or a centimeter. The lines 8 are numbered on the board 4 near their bottom consecutively beginning with one. The line 8 designated 1 will be positioned at the unit length distance 40 from the face of the spring clamp 5. The preferred distance unit is the inch.

In measuring the length of a lace curtain, for instance, one edge is clamped in the spring clamp 5 and the edge to be measured is pulled 45 longitudinally along the board 4. The length

of the curtain is then readily determined as being that represented by the line 8 with which the free edge of the curtain comes in coincidence. The curtain dimension desired is thus determined by simply reading the 55 numeral indicated. In this process the curtain must not be pulled, so as to stretch it. If the length of the curtain has been measured by the method indicated, the width may also be similarly measured. Since it is known 60 that in the washing process of the curtain that it will shrink and since it is necessary to have the curtain returned to the customer having the same dimensions that it had when it was received by the laundry or dry cleaning plant, it becomes necessary for the plant 65 to determine the dimensions of the curtain when it is received by the plant. After the curtain has been washed and shrunk thereby, 70 it is stretched by the plant to its original dimensions. In other words the curtain is measured in its soiled state on its reception by the plant. In order to conveniently designate the dimensions of the curtain I have 75 provided the tags 9, which may be any shape, 80 but which are indicated as being rectangular. The tags may be made of fabric or other material. Fabric is preferable. On the tags 9 are placed by perforating, stenciling, printing or other means, numerals which will represent length designations. In the tags 9 are formed the perforations 10, which permit 85 detachably securing the tags 9 to the hooks 7. A great many such tags may be secured to each hook. The numbers on the tags on each hook are the same and these numbers correspond with the numbers on the lines 8 near 90 the hook. In other words the hook, six inches from the spring clamp 5 will have tags with the numbers 6 thereon, hooked thereon. The hook that is eight inches distant from the spring clamp 5 will have the numeral 8 indicated thereon, etc.

The operator in measuring the curtain, as 95 previously indicated desiring to indicate the length on the curtain simply removes the tag from the hook opposite the free edge of the curtain, that is if the curtain is twelve inches long, the tag bearing the 12 will be removed 100 from one of the hooks 7, and this tag will be

secured to the curtain near its edge. It may be secured by stitching or pinning or any other convenient means. Instead of the hooks 7, pockets 11 may be used for storing the tags 9. The pockets are wide enough to permit the placing of the tags 9 therein. These pockets may be preferable to the hooks because a lace curtain cannot be caught and possibly torn on a pocket; said catching and tearing may happen with the use of hooks.

What I claim and mean to secure by Letters Patent is:

A device of the character described comprising a board having a spring clamp secured thereto at one end and parallel lines formed thereon equi-distant from each other and from the zero designation under said spring clamp, said lines being designated by numerals indicating the distance of the line that they represent from the zero designation under the spring clamp, hooks secured to said board on said lines, co-operative tags having perforations therein secured to said hooks, the tags on a hook having the same numerical designation imprinted thereon as the line on which the hook is secured.

In testimony whereof I affix my signature.
PAUL LUNGSTRAS.
